UNITED STATES PATENT OFFICE.

WOOD FREEMAN, OF SEATTLE, WASHINGTON.

GREASE-GUN.

1,127,751.

Specification of Letters Patent.

Patented Feb. 9, 1915.

Application filed July 19, 1913. Serial No. 780,093.

To all whom it may concern:

Be it known that I, WOOD FREEMAN, a citizen of the United States, residing at Seattle, in the county of King and State of Washington, have invented certain new and useful Improvements in Grease-Guns, of which the following is a specification.

The object of my invention is to provide a grease gun which shall be easily and quickly filled and emptied either with liquid or solid grease without the common annoyance of getting the grease on the hands. Also to provide a gun that shall be compact and simple to operate and which shall not require the separating of the parts from each other to fill or empty.

The mechanism of the gun is fully described as follows and is shown in the accompanying drawings.

20 Figure 1 shows a side elevation of the grease gun as normally used. Fig. 2 shows a central longitudinal section of the outer cylinder with a side elevation of the inner cylinder showing the piston pulled back 25 and the pin in the slot, but not in the recess. It also shows the elongated slot in the side of the inner tube. Fig. 3 shows the gun with the nozzle unclasped, and the inner tube pushed out ready to be 30 plunged into the grease. Fig. 4 shows a detail of the pin and bayonet slot together with the slot in the inner tube, shown also in Figs. 2 and 3. Fig. 5 is a longitudinal central section of the piston and upper end 35 of the inner tube. Fig. 6 shows a detail of the slot and recess and pin through a section taken on the line 6-6 of Fig. 4. Fig. 7 shows a section of the gun taken on a line 7-7 in Fig. 4. Fig. 8 shows a 40 force drive for use on the larger guns to push the piston home. Fig. 9 shows the slot of the piston rod and the rack inserted on which the small pinion works.

Similar numerals refer to similar parts throughout the several views.

1 is the outer cylinder or barrel of the gun and 2 is the inner cylinder which works easily but closely in the outer barrel, the inner barrel having a part of its side cut 50 away the entire length forming the slot 11 the edges of which are sharpened as shown Fig. 7 to permit the piston leathers 9', 9² to fit tightly against the outer barrel.

At the upper end of the inner cylinder 55 is the disk 3 which forms a head for the same and in which is the recess 4' and

the slot 4. The pin 5 on the piston rod 6 cooperates with the recess to push the inner cylinder out of the outer cylinder. On the piston rod is a disk 7 shown in Fig. 5 located under the head of the inner cylinder and serves to draw the inner cylinder back into the outer cylinder after the inner cylinder has been loaded with grease. The disk is held on the piston rod by a sleeve 8 which in turn is held in place by the piston proper. The piston is made up of three metal washers 9 and two leather washers 9', 9² the latter being cupped in opposite directions so as to suck and expel 70 grease without leakage.

The piston rod has a stop formed by the handle 10 which prevents the inner cylinder from being pushed entirely out of the outer cylinder. The slot 11 in the inner 75 cylinder allows the inner cylinder to be forced its entire length into the pail of grease and allows the grease to fill completely to the head of the inner cylinder. By a slight rotation of the piston or barrel 80 a cylinder full of grease is cut out which may be withdrawn into the outer cylinder.

At the lower end of the outer cylinder is a cap 12 hinged at one side and provided with a clasp 14 at the other, arranged to 85 fit over a cam provided at the lower end of the outer cylinder opposite the hinge. Secured to the cap is the nozzle 13.

In case of larger guns or with heavy grease it is sometimes needful to have an 90 easy method of forcing the piston home. Such a device is shown in Fig. 8 which is a simple rack and pinion the rack being made separate and inserted in a slot in the piston rod and the small pinion working in the rack in the piston rod and driven by the crank on the side. The pinion and crank are both fastened on a journal of sufficient length to allow the crank to swing freely without touching the side of the gun. 95 The journal passes through a boxing which can be slid back and forth in a horizontal slot by means of a cam as shown, and thus the pinion may be made to engage or disengage the rack at will.

To operate the gun clasp the barrel of the gun with the left hand and the piston rod handle in the right and pull the piston up as far as possible, then turn the handle to the right keeping it pulled back as far 110 as possible until the pin drops in the slot 4; then turning it still farther to the right

- place the pin in the recess by which means the inner tube may be pushed out of the outer cylinder. Then unclasp the nozzle or hinged cap and swing it back out of the way. Push the piston downward which will also push the inner tube out of the outer tube. Plunge the inner tube down in the pail of grease as far as the bottom of the outer tube. Now give the piston a slight 5 turn to the right by which movement the grease is cut out from the pail of grease and the inner tube may now be drawn back into the outer cylinder. Give the lower end of the gun a wipe across the edge of the pail which will free it from adhering 10 grease. Fasten the cap tightly by means of the cam clasp over the end of the gun, turn the piston quickly to the left which disengages the pin from the recess and 15 allows the piston to be pushed home by which means the grease is expelled.

This grease gun is self-contained in that the parts are never dismantled for charging and the inner cylinder or charging member 20 is extruded outwardly and withdrawn into the outer cylinder through the instrumentality of the piston rod on the opening of the closure or hinge cap 12 which carries nozzle 13. The fact that the outer cylinder becomes 25 a handle for the scoop member or inner charging cylinder when the device is used to scoop up the grease renders the device cleanly and precludes the possibility of mixing with the grease any dirt, grit or other 30 material foreign to grease and extremely detrimental to those machine parts where the grease is used. By the use of this scoop feature, the gun is extremely easy to fill and requires from one-third to one-fifth the time 35 consumed with any other gun; the time varying with the specific gravity of the grease handled.

Various changes may be made in the form, proportions and details of the device 40 without departing from the spirit of my invention since I do not consider myself limited to the precise details shown in the drawings, but am entitled to all variations thereof as may fall within the scope of the 45 claims.

Having thus described my invention, I claim:—

1. In a grease gun, an outer cylinder, an inner cylinder slidably mounted in the outer cylinder, a piston in the inner cylinder, a piston rod for said piston and means for interlocking the piston rod and inner cylinder whereby the inner cylinder may be pushed out of the outer one.
2. In a grease gun an outer cylinder and an inner cylinder, said inner cylinder being concentrically and slidably mounted within the former and a piston rod working within said inner cylinder and a disk carried by 55 said piston rod to draw back the inner tube

when same has been pushed out of the outer tube.

3. In a grease gun an outer cylinder and an inner cylinder being concentrically and slidably mounted within the former, said 70 inner cylinder having a closure provided with a recess and a piston rod provided with a pin adapted to be seated in said recess.

4. In a grease gun an outer cylinder and an inner cylinder, said inner cylinder being 75 concentrically and slidably mounted within the former and having a closure at one end provided with a slot and a recess and a piston rod moving freely within said cylinder and a pin on the piston rod adapted to pass 80 through the slot and also adapted to be seated in the recess.

5. In a grease gun an outer cylinder and an inner cylinder, said inner cylinder being 85 concentrically and slidably mounted within the former, a piston rod mounted within said inner cylinder carrying a pin for pushing said inner cylinder out of the outer cylinder, also carrying a disk for drawing said inner cylinder back into the outer cylinder, 90 said piston rod also provided with a stop which prevents said inner cylinder from being pushed entirely out of said outer cylinder.

6. In a grease gun, two cylinders, mounted 95 concentrically and slidably, each normally provided at one of its ends with a closure having an opening, the closures being at corresponding ends of the cylinders and the openings being aligned, means passing freely 100 through said openings, said means being also provided with devices arranged to engage the inner cylinder to move the same in and out of the outer cylinder.

7. An outer cylinder provided with an 105 apertured closure at one end, an inner cylinder provided with an apertured closure, and slidably mounted in the outer cylinder with the closures normally in proximity to each other, a piston slidably mounted in the inner 110 cylinder, operating means for the piston extending through the apertured closures, and coöperating interlocking means mounted on the operating means and the inner cylinder, whereby the inner cylinder may be moved in 115 and out of the outer cylinder.

8. An outer cylinder provided with an apertured closure at one end, an inner cylinder provided with an apertured closure, and slidably mounted in the outer cylinder 120 with the closures, normally in proximity to each other, a piston slidably mounted in the inner cylinder, operating means for the piston extending through the apertured closures, and coöperating interlocking means 125 mounted on the operating means and the inner cylinder, whereby the inner cylinder may be forced out of the outer cylinder.

9. An outer cylinder, provided with an apertured closure, at one end, an inner cyl- 13

inder provided with an apertured closure, and slidably mounted in the outer cylinder with the closures normally in proximity to each other, a piston slidably mounted in the 5 inner cylinder, operating means for the piston extending through the apertured closures, and coöperating interlocking means mounted on the operating means and the inner cylinder, whereby the inner cylinder 10 may be drawn back into the outer cylinder when said inner cylinder has been forced out of said outer cylinder.

10. A grease gun consisting of an outer cylinder, a piston rod working there- 15 through, a charging member connectible with and disconnectible from the piston rod and adapted to be extruded through the instrumentality of the rod beyond the hollow cylinder and to be withdrawn thereinto, means 20 for retaining the charging member in the hollow cylinder, and a piston on the piston rod operable on the contents of the charging member.

11. A grease gun comprising in combina- 25 tion a cylinder having a closure at one end provided with a nozzle, a piston rod working through the opposite end and a charging member constructed and arranged to be extruded beyond the cylinder to be charged 30 when said closure is open, and withdrawable into the cylinder through the instrumentality of the piston rod, and a piston by which the contents of the charging member may be discharged through the nozzle.

35 12. A grease gun consisting of an outer cylinder having a closure at one end provided with a nozzle, a piston rod working through the opposite end and a longitudinally slotted inner cylinder open at the end 40 toward the nozzle, means connecting the slotted cylinder and piston rod to extrude the inner cylinder outwardly when said closure is open and a piston carried by the piston rod and working in the inner cylinder 45 to project the contents of the latter through the nozzle.

13. A grease gun comprising in combina- 50 tion an outer cylinder, a piston rod working at all times through one end of the cylinder and a charging member engageable and dis- 55 engageable by the piston rod and designed when engaged with the piston rod to be extruded from the opposite end of the cylinder and to be withdrawn thereinto, means for locking the charging member within the outer cylinder, and a piston by which the 60 contents of the charging member may be projected when the piston is disconnected from the charging member.

14. In a grease gun the combination of an 65 outer cylinder provided with a removable nozzle, a sliding cylinder in the outer cylinder provided with a longitudinal slot, a piston in the slotted cylinder, a piston rod connected thereto and operative from out- 70 side the outer cylinder, means whereby through the instrumentality of the piston rod the slotted cylinder may (a) be reciprocated (b) may be given a turning movement in the outer cylinder and independent of the latter, and (c) the piston may be reciprocated independent of the slotted cylinder.

15. In a grease gun the combination of an 75 outer cylinder having a removable nozzle at one end, a piston rod working through the other end of the outer cylinder, a sliding slotted cylinder, a piston in the slotted cylinder, a piston rod working through an end of the slotted cylinder and connected with the piston, means for connecting and disconnect- 80 ing the piston rod and cylinder, whereby when connected the piston rod and cylinder will reciprocate in unison and when disconnected the piston can be reciprocated in the slotted cylinder. 85

In testimony whereof I affix my signature in presence of two witnesses.
